UNITED STATES PATENT OFFICE.

ADALBERT KRAUSS, OF NEW YORK, N. Y., ASSIGNOR TO LOUIS LEVI, OF NEW YORK, N. Y.

DESIGN FOR A LAMP-SHADE OR SIMILAR PLAITED ARTICLE.

52,513.

Specification for Design.

Patented Oct. 1, 1918.

Application filed May 18, 1918. Serial No. 235,420. Term of patent 7 years.

To all whom it may concern:

Be it known that I, ADALBERT KRAUSS, a subject of the King of Hungary, residing in the city of New York, borough of Manhattan, in the county and State of New York, have invented a new, original, and ornamental Design for a Lamp-Shade or Similar Plaited Article, of which the following is a specification, reference being had to the accompanying drawing, forming a part thereof.

The figure is a perspective view of a lamp shade or similar plaited article showing my new design.

I claim:

The ornamental design for a lamp shade or similar plaited article as shown.

ADALBERT KRAUSS.
